**PORTABLE LEVELER AND SUPPORT FOR THE
TOP OF A TILTED TEST INSTRUMENT**

Robert N. Rehlaender, 149 Cervantes Road,
Redwood City, Calif. 94062

Filed Apr. 11, 1969, Ser. No. 16,703

Term of patent 14 years

Int. Cl. D14—99

U.S. Cl. D26—1

Figure 1

Figure 2

FIG. 1 is a front perspective view of the portable leveler and support for the top of a tilted test instrument, and

FIG. 2 is a rear perspective view of the portable leveler and support of FIG. 1.

The dominant features of the invention are shown in solid lines.

I claim:

The ornamental design for a portable leveler and support for the top of a tilted test instrument, as shown.
